UNITED STATES PATENT OFFICE

2,599,227

WHEELED ANIMATED BIRD ON A CORD

Paul L. Brown, Detroit, Mich.

Application June 26, 1948; Serial No. 35,381.

8 Claims. (Cl. 46—100)

1

This invention relates in general to mechanical toys and particularly to a toy which may comprise the representation of a bird, animal, airplane or other desired figure adapted to be propelled in one direction or the other upon a supporting surface or upon a cord or the like held at opposite ends above the ground or floor. This application is a continuation in part of my pending application filed December 9, 1947, Serial No. 790,473, now abandoned.

An object of the invention is to provide a mechanical toy of the foregoing kind having a body upon which is supported a pair of vertically oscillatable wings, mechanism being provided for oscillating or flapping the wings as the toy is propelled.

A further object of the invention is to provide an improved mechanism for oscillating or flapping the wings of the toy, such mechanism being characterized by the provision of a traction wheel and a simplified actuating means for the wings driven by said wheel during rolling motion thereof.

Other objects of the invention are to provide a wing flapping or oscillating mechanism for the toy, including a traction wheel adapted to travel by gravity along an inclined cord, string, wire or other strand, and providing lever means in the form of laterally extending eccentric drive pins operatively coupled with said wings for oscillating or flapping thereof; and to provide improved and simplified means for resiliently maintaining a pivot mounting between said oscillating wings and the body of the toy.

Still another object of the invention is to provide a toy carrying a wheel having rolling engagement with a cord or strand, the toy being guided or supported on the cord or strand in such manner as to permit the cord to function as a braking or holding means for the wheel when the cord or strand is drawn taut, thus enabling the toy to be held in a fixed position, or enabling its motion to be arrested, at any selected location on the cord or strand despite the inclination thereof.

Other objects of this invention will appear in the following description and appended claims, reference being had to the accompanying drawings forming a part of this specification wherein like reference characters designate corresponding parts in the several views.

Fig. 1 is a side elevation of a toy constructed in accordance with the present invention.

Fig. 2 is a plan view of the toy shown in Fig. 1.

Fig. 3 is a fragmentary vertical section taken substantially through lines 3—3 of Fig. 2, looking in the direction of the arrows.

2

Fig. 4 is a fragmentary enlarged vertical section taken substantially through lines 4—4 of Fig. 1, looking in the direction of the arrows.

Fig. 5 is an enlarged vertical section taken substantially through lines 5—5 of Fig. 1, looking in the direction of the arrows.

Before explaining the present invention in detail it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation.

In the preferred embodiment of the invention illustrated herein, the mechanical toy, designed by way of example to simulate a bird, comprises a body 10 formed of any suitable material, such as wood, plastic or sheet metal. In the present instance the central dorsal portion of the body 10 is notched at 12 to receive a rectangular open ended roller housing 14, 15, 16 suitably secured to the body 10. The roller housing is preferably enclosed laterally by lightweight sheet metal side plates 14 and is similarly enclosed below and above by the edge walls 15 and 16 respectively. Rotatably mounted between the side plates 14 on 20 the journal pin 18 is a traction wheel or roller 20 having a knurled friction gripping rim 22 adapted to ride along an inclined string, cord or wire 24. The latter is adapted to pass essentially longitudinally through the body 10 and under the roller 20 by way of the communicating guideways 26 and 28. The guideway 26 opens within the body 10 at 30 in the region of the bird's throat and extends to the lower forward portion of the notch 12. The guideway 28 opens within the body 10 at 32 above the bird's tail and extends into the lower rearward portion of the notch 12.

It is to be noted in Figure 1 that the openings 30 and 32 are somewhat above the point of contact between the cord 24 and the under portion of the roller 20. Thus upon pulling the cord 24 taut, the body 10 will be immobilized at any desired portion along the cord 24 by friction contact between the latter and the side walls of the guideways 26 and 28. By suitably inclining the cord 24 and relaxing the tension thereon, the roller 20 will be free to roll on the cord 24 and the body 10 will travel by gravity in one direction or the other in accordance with the direction of decline of the cord 24. The body 10 is suitably weighted at its belly portion 34 so as to lower the

center of gravity and to maintain the toy on a level keel as it rides along the cord 24.

The journal pin 18 is suitably secured to the roller 20 for rotation therewith and extends laterally through the side plates 14 to provide the paired lateral eccentric wing actuating projections 36, disposed angularly to the journal axis 18. Each wing actuating projection extends through and rides in the longitudinal guide slot 37 provided therefor between the longitudinal guide bar 38 and the under side of its respective pivotally mounted wing 39, so as to impart an oscillating or flapping wing motion upon rotation of the roller 20. Each guide bar 38 is spaced from the under surface of its respective wing 39 sufficiently to provide the slot 37 and is secured at its upturned forward and rearward ends 40 and 41 respectively to the wing 39.

The wings 39 are preferably fabricated from suitable light weight material and are each essentially the same in construction and operation, being obviously mirror images of each other. Accordingly, a discussion of one wing 39 will suffice for both. The longitudinally extending rounded base or shoulder portion 42 of each wing 39 pivotally abuts the adjacent side plate 14 and provides a longitudinal outward opening channel or hook means 43. Articulation between the rounded base 42 and its respective side plate 14 is permitted by an elastic band 44 which resiliently and detachably holds each wing 39 pivotally against the side plates 14. The band 44 extends under tension along the channel 43 of each wing 39 and around the upper portions of the paired side plates 14. The forward and rearward edges of the latter are spaced at 46 and 48 respectively from the adjacent edges of the notch 12 to receive the band 44, and are notched at 50 and 52 respectively to retain the band 44 in position.

In operation of the present invention, one end of the cord 24 may be anchored at a suitable height, as for example upon the wall of a room, and the opposite end grasped in the hand with the cord 24 inclined from the point of anchorage. With the bird positioned near the point of anchorage it will be apparent that it will travel down the cord 24 by gravity, with the wheel 20 in rolling engagement with the cord 24. As the wheel 20 rotates during the travel of the bird down the cord 24, the angular wing actuating projections 36 will revolve eccentrically around the axis of rotation of the pin 18 and will oscillate or flap the wings 39 in a vertical direction.

By suitably determining the tension in the cord 24, the operator of the toy may apply a braking or holding action to the roller 20 so as to arrest its travel down the cord 24 or hold it in any given fixed position thereon. Upon removing somewhat the tension on the cord 24, the toy will be released to travel down the cord by the force of gravity.

Although the present invention is illustrated herein by means of a bird-type toy having the traction wheel 20 adapted to roll along a cord 24, it will be apparent to those skilled in the art that the spirit of the present invention may be embodied in other types of toys. For example, the toy may be readily modified to adapt the wheel 20 for rolling along a floor or rail or other supporting surface rather than the cord 24 if desired.

I claim:

1. A mechanical toy comprising a body, oppositely extending wings pivotally mounted on the

body, a traction wheel, axle means journalled on said body and secured to said wheel for rotation therewith, means for oscillating said wings upon rotation of said wheel including oblique extensions of said axle means engaging said wings, and means provided by said body for guiding a cord upon which said wheel has rolling engagement.

2. A mechanical toy comprising a body, oppositely extending wings pivotally mounted on the body, a traction wheel, axle means journalled on said body and secured to said wheel for rotation therewith, means for oscillating said wings upon rotation of said wheel including oblique extensions of said axle means engaging said wings.

3. A mechanical toy comprising a body, oppositely extending wings pivotally mounted on the body, said wings having guide slotted appendages on the underside thereof, a traction wheel, axle means rotatable with said wheel and journalled on said body, and lateral extensions of said axle means movable within said guide slots eccentrically of said axle means for oscillation of the wings upon rotation of said wheel.

4. A mechanical toy comprising a body, oppositely extending wings projecting from the sides of the body, yieldable means for pivotally mounting said wings on the body, a traction wheel, and axle means mounting said traction wheel within a recess formed in said body, said axle means having lateral extensions projecting at an angle to the axis of rotation of the traction wheel, each of said lateral extensions projecting beyond the sides of the body and engageable with a wing to oscillate the same upon rotation of the traction wheel.

5. A mechanical toy comprising a body, oppositely extending wings terminating adjacent said body in hook portions, an elastic band anchored in said hook portion and embracing a portion of said body to hold said wings yieldingly in pivotal relation to said body, a traction wheel, and axle means mounting said traction wheel within a recess formed in said body, said axle means having lateral extensions projecting at an angle to the axis of rotation of the traction wheel, each of said lateral extensions projecting beyond the sides of the body and engageable with a wing to oscillate the same upon rotation of the traction wheel.

6. A mechanical toy comprising a body, a cord threaded through the body for supporting the toy in simulated flight, oppositely extending wings projecting from the sides of the body, yieldable means for pivotally mounting said wings on the body, a traction wheel having rolling engagement with the cord, and axle means mounting said traction wheel within a recess formed in said body, said axle means having lateral extensions projecting at an angle to the axis of rotation of the traction wheel, each of said lateral extensions projecting beyond the sides of the body and engageable with a wing to oscillate the same upon rotation of the traction wheel.

7. A mechanical toy comprising a body, a cord threaded through the body for supporting the toy in simulated flight, oppositely extending wings terminating adjacent said body in hook portions, an elastic band anchored in said hook portions and embracing a portion of said body to hold said wings yieldingly in pivotal relation to said body, a traction wheel having rolling engagement with the cord, and axle means mounting said traction wheel within a recess formed in said body, said axle means having lateral extensions projecting at an angle to the axis of rotation of the traction wheel, each of said lateral extensions projecting

beyond the sides of the body and engageable with a wing to oscillate the same upon rotation of the traction wheel.

8. A mechanical toy comprising a body, a cord threaded through the body for supporting the toy in simulated flight, oppositely extending wings projecting from the sides of the body, yieldable means for pivotally mounting said wings on the body, a traction wheel having rolling engagement with the cord, and axle means mounting said traction wheel within a recess formed in said body, said axle means having lateral extensions projecting at an angle to the axis of rotation of the traction wheel, each of said lateral extensions projecting beyond the sides of the body and engageable with a wing to oscillate the same upon rotation of the traction wheel, and longitudinally spaced cord guide means provided by said body before and behind said wheel and disposed so that a straight line passing therebetween lies above the point of contact between the wheel and the cord.
